CHARLES DEVOS,
By Nigdon Longue 1913.

UNITED STATES PATENT OFFICE.

CHARLES DEVOS, OF ST. LOUIS, MISSOURI.

AUTOMATIC SAFETY-STOP FOR LOCOMOTIVES.

1,088,013.

Specification of Letters Patent.

Patented Feb. 24, 1914.

Application filed November 11, 1912. Serial No. 730,780.

To all whom it may concern:

Be it known that I, CHARLES DEVOS, a citizen of the United States, and resident of St. Louis, Missouri, have invented certain new and useful Improvements in Automatic Safety-Stops for Locomotives, of which the following is a specification containing a full, clear, and exact description, reference being had to the accompanying drawings, forming a part hereof.

My invention relates to an automatic safety stop for locomotives, and consists in the novel construction hereinafter described and specifically designated in the appended claims.

The object of my invention is to provide an improved automatic safety stop for locomotives which, by automatically closing the throttle valve and applying the air brakes, shall avoid collisions, derailments and other accidents heretofore caused by the sudden illness or accidental incapacitation of the engineer.

In the drawings: Figure 1 is a sectional side elevation of a portion of a railway track having a portion of a locomotive mounted thereon, and showing my invention applied to the said locomotive and to the said track; Fig. 2 is a sectional plan view of a locomotive throttle-lever; Fig. 3 is a detail sectional side elevation of same, the section being taken on the line 3—3 of Fig. 2; Fig. 4 is a sectional end elevation of the parts of the railway track and locomotive shown in Fig. 1; and Fig. 5 is a sectional plan view of a portion of the track.

The numeral 1 indicates the usual rails of the railway track, 2 the ties thereof and 3 the locomotive mounted thereon.

It is obvious that the term "locomotive" embraces all known forms of locomotives or motor cars, whether propelled by steam, electricity or other motive power.

Mounted between two of the ties 2 and embedded in the ballast 4 is a trough-shaped frame 5 which is substantially U-shaped in cross section, the opposite sides of same at their upper free edges being provided with integral perforated ears 6, by means of which the said frame 5 is secured to the ties 2 by means of suitable spikes or bolts 7. Pivotedly mounted within the said frame 5 upon pins or bolts 8 are the lower ends of two parallel bars 9 pivotally connected at their upper ends by a horizontal stop-bar 10.

The numeral 11 indicates spacing-devices

mounted upon the bolts 8 in order to locate the said bars 9 centrally of the said frame.

The numeral 12 indicates one of the well known semaphore poles or posts carrying at its upper portion the usual semaphore 13, which is operated in the well known manner by means of a suitable operating-shaft 14 which extends to a switch-stand or switch-tower (not shown). Pivotedly mounted upon the bracket 15, near the base of said pole 12, is a bell-crank lever 16, the horizontal arm of which is connected by means of a rod 17 to the said semaphore 13, the vertical arm of said bell-crank lever 16 being connected by means of a horizontal rod 18 to one of the bars 9 carrying said stop-bar 10. The said stop-bar 10 is adapted to be thrown laterally of the railway track and also downwardly out of the path of locomotives and cars, whenever said semaphore is thrown to a "clear" position, and to be elevated in the position shown, whenever the said semaphore is thrown to a "stop" or "danger" position.

Referring now to the operating devices carried by the locomotive (see Figs. 1 and 4) the numeral 19 indicates the usual throttle-valve lever provided with the usual locking-lever 20.

The numeral 21 indicates a bell-crank lever mounted upon the lower end of a bracket 22 depending from the roof of the locomotive cab. The vertical arm of said bell-crank lever 21 is connected by means of a cord or chain 23 with the said throttle-lever 19, by said cord being wrapped about the free end of said throttle-lever and at the same time around the said locking-lever 20. Connected to the horizontal arm of said bell-crank lever 21 by a vertical rod 25 is a hook 27, preferably made of metal which will permit said hook to "give" or straighten out whenever any considerable strain is imposed upon it. Said hook 27 normally depends from the locomotive in the position shown in Fig. 1, so that it will come in contact with and run beneath the said stop-bar 10, whenever said bar is in elevated position.

The numeral 28 indicates the usual engineer's valve for controlling the air brakes.

The numeral 29 indicates the extra train-pipe exhaust-valve, the control lever 30 of which is pivotally connected to the said vertical rod 25 in the cab, so that said valve 110 may be opened and closed by the movement of said rod 25.

The operation is as follows: With the parts in the position in which they are shown, my improved automatic safety stop for locomotives will automatically close the 5 throttle and apply the air brakes, and thereby avoid a collision, derailment or other accident should the engineer become suddenly ill or be accidentally incapacitated in any other manner. The stop-bar 10 whenever the 10 semaphore 13 is set to "stop" or "danger" as shown, will be held in the position in which it is shown and will be struck by the hook 27, carried by the locomotive, and as the locomotive proceeds the said hook 27 will be 15 drawn rearwardly and downwardly, drawing downwardly the vertical rod 25 and thereby opening the train-pipe valve 29 and applying the air brakes and simultaneously rotating the bell-crank lever 21, drawing the 20 cord or chain 23 tightly around the throttle-lever 19 and its locking-lever 20, and thereby withdrawing the sector latch and unlocking said throttle-lever and (as the movement of said bell-crank lever 21 continues) 25 closing the throttle-valve; thus quickly bringing the locomotive or train to a standstill. Whenever the track is clear, of course, the semaphore is down, thereby also depressing the stop-bar 10 out of the path of the 30 hook 27 carried by the locomotive. The said hook 27, being made of metal which will "give," as before stated, will of course be straightened out by the limited movement of the locomotive after the above described 35 stop-movements have taken place. In other words, the said hook 27 is flexible.

I claim:

1. The improved automatic safety-stop for locomotives, comprising the combination 40 with a railway track and a locomotive, of a horizontal stop-bar pivotally mounted on said railway track to be swung laterally and elevated and depressed, a flexible metallic hook on the locomotive normally depending

in the path of said stop-bar to run beneath 45 the same when the latter is in an elevated position, and said flexible hook adapted to be automatically straightened out after making contact with said stop-bar, a suitable connection between said hook and the throttle-valve, and a connection between said hook and the train-pipe of the air-brake system, whereby the throttle-valve will be automatically closed and the air brakes automatically applied, whenever said flexible 50 hook is brought in contact with said stop-bar. 2. The improved automatic safety-stop for locomotives, comprising the combination with a railway-track and a locomotive of a horizontal stop-bar pivotally mounted on 55 said railway track to be swung laterally and adapted to be elevated and depressed, a metallic flexible hook on the locomotive depending in the path of said stop-bar to run beneath the same when the latter is in an 60 elevated position, a suitable connection between said flexible hook and the throttle-valve, and a connection between said hook and the train-pipe of the air brake system, whereby the throttle valve will be automatically closed and the air brakes automatically applied, whenever said hook is brought in 65 contact with said stop-bar, a signal post, a semaphore, and suitable connections between said semaphore and said stop-bar, whereby 70 when the said semaphore is operated the said stop-bar will also be operated and elevated into or depressed out of the path of the said flexible hook carried by the locomotive. 75

In testimony whereof, I have signed my name to this specification, in presence of two 80 subscribing witnesses.

CHARLES DEVOS.
